UNITED STATES PATENT OFFICE.

WILLIAM MUNSTERMANN, OF HANOVER, KANSAS.

CHICKEN-COOP DOOR.

SPECIFICATION forming part of Letters Patent No. 783,972, dated February 28, 1905.

Application filed September 6, 1904. Serial No. 223,453.

To all whom it may concern:

Be it known that I, WILLIAM MUNSTERMANN, a citizen of the United States, residing at Hanover, in the county of Washington and State 5 of Kansas, have invented certain new and useful Improvements in Chicken-Coop Doors; and I do declare the following to be a full, clear, and exact description of the invention, such as will enable others skilled in the art to which 10 it appertains to make and use the same.

My invention is an improved chicken-coop door; and it consists in the construction, combination, and arrangement of devices herein-after described and claimed.

15 The object of my invention is to provide an improved chicken-coop door having a wicket, locking means therefor, and a trip-bar forming a perch adapted to be operated by the first fowl that leaves the coop, so as to cause the 20 wicket to be opened to release the other fowls.

In the accompanying drawings, Figure 1 is an elevation of a chicken-coop provided with a door embodying my improvements. Fig. 2 is a transverse sectional view of the same, taken 25 on the plane indicated by the line *a a* of Fig. 1. Fig. 3 is an elevation of the inner side of the door. Fig. 4 is a horizontal sectional view taken on the plane indicated by the line *b b* of Fig. 1; and Fig. 5 is a detail elevation 30 showing a portion of the door, the wicket provided with the shoulder, the spring to raise the wicket, and the catch between which and the shoulder the spring by its tension creates such friction as to enable the catch to support 35 the perch-bar in its elevated position, said figure omitting the lock-flange which covers said shoulder and the engaging ends of said catch, which lock-flange is shown at 9 in the other figures of the drawings.

40 The coop (indicated at 1) may be of any suitable construction. The lower portion of the door 2 of the coop is closed by a door 3, having an opening in its lower side and a wicket 5 for closing said opening. Said wicket is 45 here shown as disposed on the outer side of the door 3 and as pivoted, as at 6, to a metallic bar 7, which bar is secured to the outer side of the door. On the side of the wicket-opening 4 opposite the bar 7 are a bar 8 and

a lock-flange 9, and the free side of the wicket 50 closes between said bar 8 and said lock-flange. A spring 10 is connected to the wicket and serves to normally open the same by raising it to the position indicated in dotted lines in Fig. 2. At the free side of the wicket is a lock-shoulder 11, which when the wicket is closed 55 is engaged by a catch 12. At the upper side of the door is a bar 13, forming a perch. The same is here shown as being disposed on the inner side of the door and is pivoted at one 60 end, as at 14; but this arrangement may be modified without departing from the spirit of my invention. The perch is connected by a rod 15 to the catch 12. At the upper side of the door, on the inner side thereof, is a keeper 65 16, having an opening 17 for the insertion of a pin 18, which when it is placed in said opening bears under the perch-bar to prevent the same from operating. When it is desired to operate the device, the said pin is removed 70 from the said opening, as here shown.

The operation of my device is as follows: At night after the chickens have gone into the coop the wicket 5 is closed and the perch-bar 13 raised above the upper edge of the 75 door, thus causing the rod 15 to move the catch to the position required to engage the shoulder 11 of the wicket and lock the wicket. The tension of the spring creates such friction between the shoulder 11 and the catch 12 80 as to cause the catch, through the rod 15, to support the perch-bar in its elevated position. The door only closes the lower portion of the doorway, leaving an opening above the door, which is of sufficient height to prevent the 85 entrance of rats, weasels, and other noxious animals into the coop. In the morning the first chicken that leaves the coop flies to the upper side of the door and alights on the perch-bar 13, hence by its weight depressing the perch-bar and operating the catch 12 to cause the catch to release the wicket 5, whereupon the spring 10 opens the wicket, thus enabling the smaller fowl to readily leave the coop through the opening 4. 90

95 My improved door is particularly useful on coops which are employed for protecting hens and broods of young chickens, as it effectually

prevents the young chickens from leaving the coop until after the hen has done so and causes the hen when leaving the coop to release the young chickens, so that they can go with her.

5 From the foregoing description, taken in connection with the accompanying drawings, the construction and operation of the invention will be readily understood without requiring a more extended explanation.

10 Various changes in the form, proportion, and the minor details of construction may be resorted to without departing from the principle or sacrificing any of the advantages of this invention.

15 Having thus described my invention, what I claim as new, and desire to secure by Letters Patent, is—

1. The combination of a door having a vertically-movable wicket, means to raise the wicket, a catch to secure the wicket when lowered, a vertically-movable perch at the upper

side of the door, and a rod connecting the perch and the catch.

2. The combination of a door having a vertically-movable wicket, a spring to raise the wicket, a catch to secure the wicket when lowered, a vertically-movable perch at the upper side of the door, and a rod connecting the perch and the catch. 25

3. The combination of a door having a pivoted vertically-movable wicket, a spring to raise the wicket, a catch to secure the wicket when lowered, a vertically-movable perch at the upper side of the door, and a rod connecting the perch and the catch. 30

35 In testimony whereof I have hereunto set my hand in presence of two subscribing witnesses.

WILLIAM MUNSTERMANN.

Witnesses:

W. R. JONES,
JOHN DINGMAN.
